UNITED STATES PATENT OFFICE.

JAY H. HALL, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRIC CONTROL SYSTEM.

1,053,499.

Specification of Letters Patent. Patented Feb. 18, 1913.

Original application filed September 28, 1910, Serial No. 583,747. Divided and this application filed November 3, 1910, Serial No. 590,460. Renewed October 19, 1912. Serial No. 726,806.

To all whom it may concern:

Be it known that I, JAY H. HALL, a citizen of the United States, residing at Cleveland, in the county of Cuyahoga and State of Ohio, have invented new and useful Improvements in Electric Control Systems, of which the following is a specification.

My invention relates to motor control systems, particularly that form in which magnetically-operated switches are used to make the various connections in the motor circuit. In the usual form of such controllers one or more auxiliary contacts are used on each switch for controlling the actuating circuits of the switches, and some form of relay device is used to obtain automatic acceleration of the motor.

The objects of my invention are—1st. To provide a system by which the motor may be reversed and controlled without the use of auxiliary contacts or relay devices to control the actuating circuits of the various switches. 2nd. To provide for accelerating the motor automatically by a control responsive to the current in the motor circuit and under the control of the operator without the use of the usual relay devices. 3rd. To provide a reversing switch on whose contacts a circuit is never established nor broken, and to cause the breaking of the motor circuit to always occur at one pair of contacts which may be carried by a main switch. To accomplish this last object it is evident that the main switch must never operate until the reverser is in its proper position, and that the reverser must never operate while any current is flowing through the motor circuit.

I will now describe my invention in detail, referring to the accompanying drawings, in which—

Figure 1 is a wiring diagram embodying my invention. Figs. 2 and 3 show in section and elevation the form of reverser switch which I prefer to use. Figs. 4 and 5 show in section and elevation one form of accelerating switch, and Figs. 6 and 7 show in section and elevation an accelerating switch, in which the energizing windings are differently arranged.

Referring first to Figs. 2 and 3 which show the form of reverser which I prefer to use, d' is a frame of magnetic material having two parallel members provided with the

two bosses or poles d^2 and d^3 on opposite sides of the armature d^4 , which is pivoted between the said members on the pin d^{18} and is arranged to be attracted to one boss or the other. The armature d^4 carries two insulated contacts d^6 and d^8 supported on the insulating members d^7 . These contacts connect on one side with the stationary contacts d^9 and d^{18} , and on the other side with the stationary contacts d^{10} and d^{11} (Fig. 1). The stationary contacts are mounted on an insulating support d^{14} , as also are the terminals d^{15} and d^{16} , joined by the flexible connectors f to the contacts d^6 and d^8 . The bosses d^2 and d^3 are surrounded by the windings d^{10} and d^{11} , respectively; and the boss d^{17} to which the armature d^4 is pivoted surrounded by the winding d^{12} .

From Fig. 1 it is seen that the windings d^{10} and d^{11} are connected in series across the supply mains as follows: From the positive main through the wire 1, the contact d^8 , the winding d^{10} , the point O, the winding d^{11} , the contacts d^{10} and d^{11} , the wire 5, and the motor-field F to the negative main. The winding d^{12} is in the armature branch of the motor circuit, as will be presently explained, so that each reversal of the armature rotation will reverse the flow of current in the winding, the object of this coil being to prevent the operation of the reversing switch when any motor current is flowing through it. The winding d^{12} has one terminal connected to the contact d^6 , and the other to the movable contact of the main switch S, actuated by the winding S^a having one terminal connected to the wire 17 leading to the segments m^3 and m^6 of the master switch M, and the other terminal to the wire 13 or other connection leading to the contact d^8 , so that it may be connected to the positive or the negative main according as the contact d^6 engages the fixed contact d^8 or d^9 .

Referring now to Figs. 4 and 5 which illustrate one form of accelerating switch, S^w is an open rectangular frame of magnetic material secured to the insulating support S^2 . This frame has the two bosses or poles S^3 and S^4 projecting toward each other and spaced apart so as to receive between them the body of the plunger or armature S^5 and provide at opposite sides thereof the air gap S^{12} next to the boss S^3 , and the air gap

S^{14} next to the boss S^4 . The latter boss is preferably the inner end of the plug S^{23} screwed into the side of the frame S^w . By means of this plug the air gap S^{14} may be made greater or smaller. The boss S^8 may be made also adjustable. The plug S^{23} has a non-magnetic bushing S^6 in which the lower reduced end S^{22} of the plunger reciprocates.

The plunger body is connected by the rod 10 of non-magnetic material S^7 to the switch arm S^8 pivoted to the frame S^w at the pin S^9 and arranged to engage the fixed brush or contact S^{13} , also secured to the support S^2 . The shoulder S^{10} on the rod S^7 rests on 15 the frame and prevents the plunger S^6 from falling beyond a fixed limit.

The winding S^{11} surrounds the plunger S^6 at or near the place where it changes its cross-section, that is, where the extension 20 S^{22} joins the body. The winding S^{20} surrounds the boss or pole S^8 , having its area preferably different from that of the upper face of the armature S^5 .

On Fig. 1 it is seen that the acceleration 25 windings S^{11} , S^{11a} , and S^{11b} have each one terminal connected to the fixed contact of a switch which next precedes it in operation, and the other terminal connected to the movable member of the switch which it actuates 30 and to one terminal of a section of resistance.

The windings S^{20} , S^{20a} , and S^{20b} have each one terminal connected to the wire 13 and their three remaining terminal connected to the segments m^6 , m^7 , m^8 , respectively, of the 35 master switch M .

It has been found that the switch shown in Figs. 4 and 5 has the remarkable property of retaining its contacts open when the winding S^{11} is excited beyond a predetermined 40 value and of causing its contacts to close when the excitation in the winding, is lowered to that value. I have found that a very small amount of excitation of the winding S^{20} will cause the magnetic pull on the armature S^5 45 to be greater in the gap S^{14} than the gap S^{12} for any excitation of the coil S^{11} that can operate the switch arm; but if the winding S^{11} has operated the switch, the excitation 50 of the winding S^{20} cannot cause the switch to open unless its excitation is very large. This effect is obtained when the flux set up by the winding S^{20} opposes the flux set up by the winding S^{11} . Therefore, a small amount of excitation in the winding S^{20} 55 prevents the switch from operating regardless of the amount of current flowing in the winding S^{11} .

In Figs. 6 and 7 the parts are the same as in Figs. 4 and 5, except that the winding 60 S^{20} has been removed from the boss S^8 and the winding S^{21} has been placed beneath the winding S^{11} , the winding S^{21} corresponding in its connections and functions to the winding S^{20} . If the excitation of the winding 65 S^{21} locks the switch open, it is evident that

any additional flux set up by the winding S^{11} in the same direction will still lock the switch open.

Referring now to Fig. 1, as soon as the master-controller handle o is moved to the position 1, the winding d^{10} is energized by current from the positive through the winding d^{10} , the wire 12, the auxiliary contacts h and h' of the switch S , the wire 12', the contacts m^2 and m' to the negative. This 75 causes the reversing switch to operate, connecting d^5 to d^8 , and d^6 to d^9 . When the controller handle moves to position 2, current flows from the positive through the wire 1, the contacts d^8 and d^9 , the winding d^{12} , one terminal of the switch S , the wire 13, the windings s^{20} , s^{20a} , and s^{20b} in parallel, the wires 14, 15, and 16 in parallel, the contacts m^6 , m^7 , and m^8 and the arm o to the negative on the contact m' . Current also 80 flows from the positive through the wire 1, the contacts d^8 and d^9 , the winding d^{12} , the solenoid S^a of the switch S , the wire 17, and the contacts m^3 to m' to the negative, which 85 closes the switch S . The connection is 90 broken between contacts m' to m^2 so that current ceases to flow through the wires 12 and 12', and the winding d^{10} is placed in series with the winding d^{11} . The current through the windings s^{20} , s^{20a} , and s^{20b} 95 prevents their respective switches from operating until they are deenergized; but on the closure of the switch S , current flows from the positive through the wire 1, the contacts d^6 and d^8 , the winding d^{12} , the contacts of 100 the switch S , the operating winding S^{11} of the switch S' , the wire 2, the resistance R' , R^2 , and R^3 , the wire 3, the motor armature A , the wire 4, the contacts d^6 and d^8 , the wire 5, and the series field F to the negative. 105 This circuit connects all of the resistance in series with the motor and starts the motor at its lowest speed.

As long as the master controller handle remains in the position 2, the switch S' , cannot 110 operate on account of the winding S^{20} being energized. If the master controller arm o is moved to the position 3, the winding s^{20} is deenergized, and the switch S' is allowed to close providing the current in the winding 115 S^{11} is below a predetermined value. Upon the closure of the switch S' , the winding S^{11a} of the switch S^2 is energized, at the same time short-circuiting the resistance R' and causing the motor to increase its speed. 120

The switch S^2 will not operate until the master controller arm o is moved to the position 4, when its winding S^{20a} is deenergized, allowing the switch to close as soon as the current in the winding S^{11a} diminishes 125 to a predetermined value. This switch then closes, energizing the winding S^{11b} of the switch S^3 , and short-circuiting the resistance R^2 and further increasing the speed of the motor.

5 The switch S^3 is prevented from operating until the master controller arm o is moved to the position 5, at which time its winding S^{20b} is deenergized, allowing the switch to close and short-circuiting the last section R^3 of the resistance.

10 The action of the windings S^1 , S^{1a} , and S^{1b} on their respective switches is such that a large current will cause the switch to remain open, and a smaller current which may be adjusted to a predetermined value on each switch will cause the switch to operate, as above explained, provided the windings S^{20} are deenergized.

15 On moving the controller arm to the off position, the main switch S opens, which opens the motor circuit, thereby causing all the switches S' , S^2 , and S^3 to drop out, the reversing switch remaining in its operated position.

20 On moving the controller handle to the position 6, the positive is connected to the point O through the contacts m^4 and m^2 , and the wire 12', the auxiliary contacts h and h' of the switch S , and the wire 12, thereby energizing the winding d^{11} and short-circuiting the winding d^{10} , which causes the reversing switch to operate, connecting its contacts d^5 and d^6 to its contacts 30 d^9 and d^{10} , respectively.

25 On moving the controller arm to position 7, the winding S^a is energized from the positive through the contacts m^4 and m^5 , the wire 17, and the contacts of the reversing switch to the negative, through the wire 5 and the field F . This causes the switch S to operate, closing the motor circuit through all the starting resistance, but the current now flows through the armature in the opposite direction from that before through the following circuit: From the positive through the wire 11, the contacts d^9 and d^8 , the wire 4, the armature A , the wire 3, the starting resistance, the wire 2, the operating 40 winding of the switch S' , the contacts of the switch S , the winding d^{12} , the contacts d^5 and d^6 , the wire 5, and the series field F to the negative. The direction of current has been reversed through the winding S^{11} and 45 it is also reversed through the windings S^{20} , S^{20a} , and S^{20b} , since the positive connection is now at the master controller.

50 As the master switch arm is moved step by step to positions 7, 8, 9, and 10, the switches S' , S^2 , and S^3 operate as before to short circuit the starting resistance and bring the motor up to speed. On moving the master switch arm o to the off-position, the switch S opens the motor circuit and the accelerating switches drop out. If the master switch arm is moved quickly from the off-position to position 5, the reversing switch will operate, and then the main switch S will close, all the windings S^{20} , 55 S^{20a} , and S^{20b} will be deenergized, but the

winding S^{11} will operate the switch S' only when the motor current is below a predetermined value. The operation of this switch energizes the operating winding of the switch S^2 . In the same manner this switch 70 does not operate until the motor current is again below a predetermined value. Likewise when the switch S^2 closes the operating winding of the switch S^3 is energized, but this switch does not close until the motor current is again reduced to a predetermined value and the acceleration of the motor has taken place automatically and in the shortest time without exceeding a safe value of motor current. If the arm of the master switch is reversed quickly to position 6, although the winding d^{11} is now fully energized it will not operate the reverser until the switch S has opened and the motor current actually interrupted, thereby deenergizing the winding d^{12} .

75 It often occurs that, if the motor circuit contains a large inductive resistance, the arc at the contacts of the switch S will continue to exist for some little time until the switch 90 has reached its maximum opening position, but the reverser with the construction shown will not operate until the arc has been extinguished and the motor current definitely interrupted. This action of preventing the 95 operation of the reversing switch does not, therefore, depend upon the position of the switch S , but upon the condition of whether or not current is flowing in the motor circuit.

100 It will be noticed that the switches S' , S^2 , and S^3 are held closed by the motor current and will, therefore, not open until the current in the motor circuit ceases to flow thereby preventing any arc at their contacts at the opening of the switch. For the same 105 reason the reversing switch cannot operate as long as any motor current flows, and no arc will be formed at its contacts when it is allowed to operate.

110 I have shown the preventive operating windings s^{20} , s^{20a} , and s^{20b} connected in multiple and deenergized one at a time by the movement of the master controlling handle. It will be readily understood by those skilled in the art that these windings may 115 be connected in series or in other combinations with proper connections on the master controller to deenergize the windings at will as the master controller handle is moved from one position to the next.

120 When the winding d^{11} is energized and the armature d^4 is attracted to the boss or pole d^8 as hereinbefore described, the winding d^{10} is short-circuited, and a magnetic flux is set up through the path c' . This will 125 cause the armature d^4 to be attracted to the boss d^8 . Upon the closure of the main switch the motor current will flow through the winding d^{12} which is connected to set up 130 a magnetic flux in the direction of the path

c^2 , having the double barbed arrows. This will increase the flux tending to hold the armature in contact with the boss d^3 . If now the positive connection is removed from the point O, the two windings d^{10} and d^{11} are connected in series and equally excited, the winding d^{10} being so connected that it will tend to set up a flux in the path c^4 . This flux however is opposed in the central arm 10 of the magnetic circuit through the armature by the flux set up by the windings d^{11} and d^{12} , and will be forced into the path marked c^3 , and due to the small gap between the armature and the boss d^3 this flux will 15 help to hold the armature d^4 in contact with the boss d^3 . If now the point O should be connected to the negative main, the winding d^{11} would be short-circuited, and the winding d^{10} would be fully excited. The flux still 20 set up by the winding d^{12} , however, will still oppose the flux set up by the winding d^{10} in the central arm of the circuit, and force the increased flux of the winding d^{10} to flow in the path c^3 which will hold the armature in 25 contact with the boss d^3 as long as any motor current flows in the winding d^{12} . If the motor current is now interrupted, the winding d^{12} will be deenergized and the flux set up by the winding d^{10} will follow 30 the path c^4 , thereby attracting the armature d^4 to the boss d^2 and reversing the connections to the armature. If now the motor circuit is again established, the direction of current through the winding d^{12} will be 35 reversed, and the flux set up in this coil will now be in the direction shown by the path c^5 , which will assist the flux set up by the winding d^{10} in holding the armature in contact with the boss d^2 . The armature will 40 continue to remain in this position as long as any motor current flows regardless of whether the windings d^{10} and d^{11} are excited or not. When the flux set up by the winding d^{12} is flowing in the path c^5 any flux 45 set up by the winding d^{11} which would tend to flow in the path c' would now be opposed by the flux of the winding d^{12} in the central arm of the magnetic circuit, and the flux in the winding d^{11} would be directed 50 into the path c^3 , which would help to hold the armature d^4 in contact with the boss d^2 . Generally speaking, whenever the winding d^{12} is deenergized the armature d^4 will be attracted to that boss whose winding has the 55 excess excitation, but when the winding d^{12} is energized it will hold the armature in contact with the boss to which it has been previously attracted, and the windings d^{10} and d^{11} then both operate to hold the armature 60 in that position. The same effect may be secured by placing a winding similar to d^{12} on the bosses d^2 and d^3 adjacent to the windings d^{10} and d^{11} . In this arrangement only one of these windings d^{12} will be energized at a time, and that winding will be 65

energized which is on the side to which the armature d^4 has been just attracted. In the diagram these windings would be located in the wires 1 and 11, and the flux set up by them would be in the same direction as set 70 up by the windings d^{10} and d^{11} .

Assuming that the winding d^{11} has been energized and the armature d^4 attracted to the boss d^3 , if the windings d^{11} and d^{10} are now connected in series, the flux set up by the winding d^{11} will flow in the path c' , and the flux set up by the winding d^{10} will tend to flow in the path c^4 but since the reluctance of the path c' will be much less than that of the path c^4 due to the armature d^4 being in contact with the boss d^3 , the flux in the central arm of the magnetic circuit set up by the winding d^{11} , and the flux from the winding d^{10} will be directed into the path c^3 , and the two windings, therefore, tend to hold the armature d^4 with the boss d^3 . I have pointed out before that this effect takes place when the winding d^{12} is energized, but I wish also to point out that this effect will take place when only the two windings 80 d^{10} and d^{11} are energized in series, which occurs when the master controller handle in Fig. 1 is moved to the position 2. The advantage of this action is that after the reverser has operated, the two windings can 85 be thrown in series, maintaining approximately the same pressure between the reverser contacts, but cutting down the amount of heating in the operating windings.

I do not limit my invention to details and 90 combinations shown and described.

This application is a division of my application, Serial Number 583,747, filed September 26, 1910.

I claim—

1. In a motor control system, a reverser having two windings for operating the reverser in one direction or the other, a main switch for closing the motor circuit, an energizing winding therefor, a master switch for controlling the windings and means, when one of the reverser windings is energized, for preventing the energizing of the main switch winding until the reverser is 105 in its proper position.

2. In a current varying controller, a circuit, a resistance for controlling the current in the said circuit, a set of switches for controlling the resistance each having two windings, one of which operates the switch 110 only when the current in the winding is below a certain predetermined value, the other winding when energized preventing the operation of the switch, and means for energizing and deenergizing the windings.

3. In a current varying controller, a circuit, a resistance for controlling the circuit, a set of switches arranged to close successively for controlling the resistance, each switch having two windings, one being con- 125 130

5 nected in the circuit and adapted to close the switch only when the current in the winding is below a predetermined value, the other winding being adapted to prevent the operation of the switch when energized, and a master switch for deenergizing said second windings at will.

4. In a motor control system, a circuit, a resistance therefor, a main switch, a set of 10 resistance controlling switches each having a winding which operates its switch only when the current in the said winding is below a predetermined value, and means for controlling the operation of each switch at 15 will.

5. The combination of a circuit, a reverser therefor, a governing circuit for the reverser, and a winding in the controlled 20 circuit which when energized will cause the windings in the governing circuit to become maintaining windings when energized.

6. In a circuit, an element to be reversed, a reverser therefor, operating windings for the reverser, and a maintaining winding in 25 which the current is reversed each time the reverser is operated in one direction or the other.

7. In a motor control system, a reverser 30 therefor, means for operating the reverser, magnetic means for holding the reverser in its operated position so long as current flows through the motor, and means for changing the polarity of the magnetic means each time the motor is reversed.

35 8. In a motor control system, a circuit containing a reverser, operating windings for the reverser and means for energizing them, a maintaining winding in the circuit having a magnetic circuit in common with 40 the operating winding last excited.

9. In a motor controller, a reverser whose operating windings are connected in series across the source of current supply, means short-circuiting one of the windings for operating the reverser in one direction, and 45 means for subsequently opening the short-circuit causing both windings to act to hold the reverser in its operated position.

10. In a motor control system, a circuit, a reverser having its contacts in the circuit, 50 operating windings for the reverser, means short-circuiting one of the windings for operating the reverser to run the motor in one direction, means for subsequently opening the short-circuit to cause both windings 55 to hold the reverser in its operated position, and an additional winding in the circuit which causes the reverser to remain in its operated position as long as any current flows in the circuit.

60 11. In a motor control system, a reverser, operating windings for the reverser and magnetic means for causing the windings to become ineffective to reverse the motor when current flows through the motor.

65 12. In a motor control system, a reverser having contacts in circuit with the motor, operating windings for the reverser normally connected in series across the source of supply, means short-circuiting one of the 70 windings for operating the reverser, and means for preventing the operation of the reverser when current flows through its contacts.

Signed at Cleveland, Ohio, this 28th day 75 of October, A. D. 1910.
